UNITED STATES PATENT OFFICE.

MICHAEL M. CROWLEY, OF SIOUX CITY, IOWA.

FEED-WATER APPARATUS FOR STEAM BOILERS.

Application filed January 22, 1925. Serial No. 3,935.

To all whom it may concern:

Be it known that I, MICHAEL M. CROWLEY, a citizen of the United States, and a resident of Sioux City, in the county of Woodbury 5 and State of Iowa, have invented certain new and useful Improvements in Feed-Water Apparatus for Steam Boilers, of which the following is a specification.

My invention relates to apparatus used for 10 supplying water to a steam boiler, and it is my object to provide mechanism for pre-heating the water and subjecting it to the action of a settling tank, designed to remove a large proportion of the impurities ordinarily found in the water, prior to its injection into the boiler.

Another object is to provide such an apparatus which is of simple, durable and inexpensive construction, and which will not increase materially the weight of a locomotive 20 to which it is applied.

A further object is to provide an apparatus having pre-heating pipes in which a constant circulation of water is maintained, 25 irrespective of the action of the injecting apparatus, in order to prevent the burning out of the said pre-heating pipes and at the same time subjecting part of the water of the forward end of the boiler constantly to 30 the direct heat of the fire box of the boiler.

My invention, as applied to a steam locomotive, involves the use of a pair of pre-heating pipes extended through the fire box of the locomotive just above the brick arch 35 thereof, each of the pre-heating tubes being connected at one end by means of a double action check valve to the front end of the boiler, and also to one of the injectors of the locomotive, and at the other end to a settling 40 tank, from which the heated water is injected into the boiler, the parts being so arranged that when one injector is applied the check valve connecting with that injector will direct a stream of water therefrom 45 through its respective pre-heating tube to the settling tank, and thence into the boiler through the injecting tube and shut off the return tube from the boiler to the check valve, the other check valve allowing circulation 50 of the water through the return tube from the boiler into the other pre-heating tube which is not being subjected to a stream of water from an injector.

A further object is to provide a novel 55 check valve adapted to perform the functions named in the foregoing objects.

A still further object is to provide a settling tank of simple and novel construction which may be readily disassembled for cleaning purposes, and which is especially 60 adapted to remove impurities from the water being injected into the boiler.

Another object is to so construct the pre-heating tubes that they may be readily cleaned. 65

Another object is to provide means for utilizing the exhaust steam from the locomotive cylinders to maintain an atmosphere around the settling tank approaching the temperature of the water within the tank, so 70 as to make up for loss of heat by radiation of the heat from the tank.

More specifically, referring to the settling tank, it is my object to provide a construction in which a tank of material such as copper, is provided with a wide annular flange 75 serving as a gasket between a steam jacket surrounding the tank, and a cover of the tank, and in which a baffle plate is provided to induce a circulation of the incoming water 80 downwardly in the tank before discharge into the injecting tube, and further to prevent a direct flow of water between the two inlets from the pre-heating tubes.

With these and other objects in view, my 85 invention consists in the construction, arrangement and combination of the various parts of my device, whereby the objects contemplated are attained, as hereinafter more fully set forth, pointed out in my claims 90 and illustrated in the accompanying drawings, in which:

Fig. 1 is a perspective view of a locomotive shown in broken lines with my apparatus installed thereon shown in heavy and 95 dotted lines.

Fig. 2 is a transverse sectional view through the fire box of a locomotive, illustrating the mounting of the settling tank thereon, and the manner of installing the 100 pre-heating tubes.

Fig. 3 is an enlarged sectional view through the settling tank, taken on the line 3-3 of Fig. 2.

Fig. 4 is a transverse sectional view 105 through the settling tank, taken on the line 4-4 of Fig. 3.

Fig. 5 is a horizontal sectional view through one of the check valves and its connecting tubes. 110

I have used the reference character 10 to indicate generally the cylindrical portion of

- the boiler of a locomotive, having the cab, 11, the saddle, 12, the valve chamber, 13, the exhaust steam cavity, 14, the exhaust nozzle, 15, the running board, 16, the crown sheet, 17, the mud ring, 18, and the boiler leg having the outer side sheet, 19, and the inner side sheet, 20, the arch tubes, 21, the arch, 22, and the injectors, 23 and 24, supported suitably from the frame of the locomotive.
- 10 Each of the injectors, 23 and 24, has the water inlet pipe, 25, the steam inlet pipe, 26, the overflow pipe, 27, and the branch pipe, 28, or 28^a through which the water is discharged from the injector. The branch pipe 15 from the injector, 24, I have referred to by the character 28^a.

I provide a pair of pre-heating tubes, 26^b and 27^b, which are extended through the fire box of a locomotive just above the arch, 22, 20 and ahead of the cab, 11. The sleeves, 28^b, are swaged into the respective legs of the boiler to receive the tubes. To the outer ends of the tubes, 26^b and 27^b, are fixed the flanges, 29, providing means for connecting 25 the tubes to their respective connecting pipes.

The tubes, 26^b and 27^b, are preferably of copper, which does not corrode as readily as iron, which is easier cleaned, and to which 30 the impurities of water do not as readily adhere and which they do not encrust.

On one side of the locomotive the elbows, 30, are provided to connect the tubes, 26^b and 27^b, to the valves, A and B, respectively. 35 Each elbow, 30, is provided with an extension, 31, aligned with that portion of the elbow, which is connected with the respective pre-heating tube and provided with a plug, 32, which is removable to allow the insertion 40 of a cleaning instrument.

Each check valve, A and B, comprises a bowl-shaped valve chamber, 33, having the two valve seats, 34 and 35, and closed at one side by means of a cover plate, 36. A double 45 faced valve, 37, has a stem, 38, slidably mounted in the boss, 39, of the chamber, 33, and a sleeve, 40, on the cover plate, 36.

A threaded, handled valve rod, 41, is mounted in the cover plate, 36, and may be 50 utilized to force the valve, 37, against its seat, 35, should the same become corroded slightly or encrusted with foreign material sufficient to prevent proper seating of the valve.

55 The chamber, 33, is provided with two necks, 42 and 43, respectively, communicating with the chamber on either side of the valve, 37, and with a neck, 44, communicating with the chamber on both sides of the 59 valve, 37, when the same is in intermediate position. The neck, 44, of each valve is connected with the elbow, 30, of the respective pre-heating tube, as shown in Fig. 1, and to the two necks, 43, is connected a Y-shaped pipe fitting, 45, serving to provide communica-

cation between the two valves and the return tube, 46, tapped to the boiler at 47. The necks, 42, of the respective valves, A and B, communicate with the branch pipes, 28^a and 28, respectively leading from the injectors, 24 and 23, respectively. The branch pipe, 28^a, is extended under the boiler just ahead of the boiler leg, as illustrated in dotted lines in Fig. 1.

The settling tank, 48, is preferably made 75 of copper, provided at its lower end with a discharge clean-out tube, 49, closed by a blow-off cock, 50. The tube, 26^b, is connected to the settling tank, 48, by means of a short connecting pipe, 51, and the tube, 27^b, by 80 means of a pipe, 52, extending partially around the tank and entering the tank at right angles to the pipe, 51.

Between the discharge ends of the pipes, 51 and 52, is positioned a diagonally disposed, vertical baffle plate, 53, supported from a horizontal baffle plate, 54, positioned above both of the tubes, 51 and 52, between them and the top of the tank.

The upper edge of the tank, 48, is provided with a flange, 55, which serves as a gasket between the steam jacket, 56, surrounding the tank and the cover plate, 57, closing the upper end of the tank. A short exhaust tube, 58, secured to the cover plate, 57, serves to provide communication between the tank, 48, and the injecting tube, 59, which is tapped into the boiler, 10, at 60. A bottom plate, 61, closes the lower end of the jacket, 56, and may be secured to the clean-out tube, 49, by brazing or otherwise. A drain tube, 62, secured in the bottom plate, 61, and closed by a valve, 63, serves to allow draining of condensed water from the interior of the jacket, 56.

105 The entire settling apparatus is supported on brackets, 64 and 65, secured to the side plates, 19 and 20, of the boiler leg, by means of bolts, 66, and riveted to the jacket, 56.

Steam issuing from the valve chamber, 13, 110 into the exhaust cavity, 14, is supplied through a tube, 67, tapped into the saddle, 12, and communicating with the cavity, 14, a pipe, 68, connected with the tube, 67, and a pipe, 69, secured in the jacket, 56, to the space surrounding the tank, 48, within the jacket, 56. A return tube, 70, connected to the tube, 71, secured in the jacket, 56, is tapped into the nozzle, 15, all as illustrated 115 in dotted lines in Fig. 1. The pressure of the steam issuing from the cylinders will be slightly greater at the entrance to the tube, 67, and will therefore create a circulation of a sufficient quantity of steam through the jacket, 56, to maintain the temperature surrounding the tank, 48, at a sufficient level to prevent any appreciable loss of heat from radiation from the water within the tank.

120 In the operation of my apparatus, when the injectors are not being used the pressure 125

through the pipe, 46, will cause the valves, 37, to seat against the respective seats, 35, as illustrated in Fig. 5, and will thereby establish communication between the tube, 46, and the pre-heating tubes, 26^b and 27^b. The tube, 59, is positioned slightly above the tube, 46, so that the heated water will tend to circulate through the pre-heating tubes into the tank, 48, and thence through the tube, 59, into the boiler and back through the return tube, 46. As the water circulates the baffle plate, 54, will tend to direct the current downwardly in the tank, 48, in the water, as illustrated by the arrows, 72, the water then flowing upwardly around the sides of the tank and around the edges of the baffle plate, 54, as indicated by the arrows, 73, in Fig. 3. The water in flowing through the pre-heating tubes, 26^b and 27^b, is brought to a very high temperature sufficient that it will tend to boil in the tank, 48, against the pressure of steam from within the boiler, 10. While in this condition the impurities, such as mud, carried by the water will be dropped within the tank, 48, the circulation of the water therein aiding the settling out of the impurities by the momentum of the particles.

It is a known fact that most impurities will settle out from the water within the pipes of a locomotive subjected to the ordinary pressure of a boiler, at temperatures ranging from 300 to 400 degrees Fahrenheit, so that as the water is allowed to flow down in the enlarged chamber of the tank, 48, the greater amount of the impurities will separate therefrom.

When the injector, 23, is in operation, the pressure of the water flowing through the tube, 28, will seat the valve, 37, proper of the valve, B against the pressure from the boiler, exerted through the pipe, 46, the same as in the ordinary check valve used in connection with the branch pipe of the ordinary injector. The water from the injector will thence flow through the tube, 27^b, and through the tank, 48, and the injecting tube, 59, into the boiler. The same settling of impurities will occur in this process.

While either injector is in action alone, it will be seen that a part of the pressure from the injector may be relieved through the pre-heating tube which is not in direct communication with that injector, as the tube, 26^b, where the injector, 23, is being used, and the injected water thus caused to flow through the tube, 59, and the tube, 46, into the boiler. Should this occur, it would be desirable to prevent a direct flow of water from the tube, 51, to the tube, 52. Since such a direct flow would prevent the proper functioning of the settling tank in removing the impurities, the baffle plate, 53, is therefore provided and so positioned as to obstruct the path of a current of water flowing between these two tubes.

When the injector, 24, is in operation, the valve, A, will act in the same manner as the described action of the valve, B, in connection with the injector, 23, and a current of water will be forced through the pre-heating tube, 26^b. In either case the other pre-heating tube will remain constantly filled with water to prevent burning out.

When the injectors are shut off the respective valves, 37, will return to the valve seats, 35, and check the flow of water from the boiler back through the injectors, as in the ordinary check valve. Should both injectors be used at once the return tube, 46, will be temporarily disconnected entirely from the tubes, 26^b and 27^b, and a stream of water forced through both of these tubes into the injecting tube, 59. For this purpose the injecting tube, 59, is made twice the size of the tubes, 26^b and 27^b.

The valves, A and B, are located just under the running board, 16, of the locomotive.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

By circulating the water from the forward end of the boiler through the preheating tubes and back to the boiler, the temperature of the water at the forward end of the boiler may be brought to a point more nearly equal to that of the water directly over the firebox. In the ordinary locomotive there is a considerable difference in temperature between the forward end and the rear end of the boiler, due to the concentration of heat at the rear end, and the efficiency of the locomotive is thus less than it would be were the temperatures more nearly equal. In addition to this, the unequal temperatures cause undue strains upon the sides of the boiler, necessitating frequent repairs.

In addition to providing a means for pre-heating the water to be injected for the first time into the locomotive, and for boiling out the impurities, my apparatus will constantly heat a stream of water flowing through the preheating tube from the return tube, 46, to the injecting tube, 59. In order to create such circulation the tube, 59, communicates with the boiler at a point somewhat above the level of the elbow, 47, thereby utilizing the thermo-siphon principle of water circulation. The settling tank, although it acts only on freshly introduced feed water, does not interfere with such circulation of water from the forward end of the boiler.

It will be understood that where the word "injector" is used in the claims and specifica-

tions it refers to any type of pumping means for forcing water into the boiler.

I claim as my invention:

1. In combination with a locomotive having a boiler, an injector and a fire box, an injecting tube, a return tube, a preheating tube extending through the fire box and communicating at one end with the injecting tube for conducting feed water to the boiler, 10 a valve connecting the other end of the preheating tube to the injector and to the return tube and adapted to automatically establish communication between the injector and preheating tube when the injector is in 15 action, and between the return tube and preheating tube when the injector is not in action.

2. In combination with a locomotive having an injector, a boiler and a fire box, a preheating tube extending through the fire box and communicating at one end with an injecting tube for conducting feed water to the boiler, a valve comprising a valve chamber having a centrally positioned valve 25 element separating said chamber into two compartments, said chamber having a first port communicating with one compartment and connected by a return tube to the boiler, having a second port communicating with 30 the other compartment and connecting with the injector, and having a third port, the valve element being adapted under unequal pressures from said first and second ports to move from one position where one compartment is in communication with said 35 third port, to a second position where the other compartment is in communication with said third port, said third port being connected with the preheating tube at its end opposite its communication with the injecting tube.

3. In combination with a locomotive having an injector, a boiler and a fire box, a preheating tube extending through the fire 45 box and communicating at one end with an injecting tube for conducting feed water to the boiler, a valve comprising a valve chamber having a centrally positioned valve element separating said chamber into two compartments, said chamber having a first port communicating with one compartment and connected by a return tube to the boiler, having a second port communicating with the other compartment and connecting with the 50 injector, and having a third port, the valve element being adapted under unequal pressures from said first and second ports to move from one position where one compartment is in communication with said third port, to a second position where the other compartment is in communication with said 55 third port, said third port being connected with the preheating tube at its end opposite its communication with the injecting tube, 60 and a threaded rod extending into said valve 65

chamber and adapted to engage the valve element to move it forcibly against one of its seats.

4. In combination with a locomotive having an injector, a boiler and a fire box, a preheating tube extending through the fire box and communicating at one end with an injecting tube for conducting feed water to the boiler, a valve comprising a valve chamber having a centrally positioned valve 75 element separating said chamber into two compartments, said chamber having a first port communicating with one compartment and connected by a return tube to the boiler, having a second port communicating with the other compartment and connecting with the injector, and having a third port, the valve element being adapted under unequal pressures from said first and second 80 ports to move from one position where one compartment is in communication with said third port, to a second position where the other compartment is in communication with said third port, said third port being connected with the preheating tube at its 85 end opposite its communication with the injecting tube through the medium of an elbow having a plugged clean-out extension aligned with the preheating tube.

5. In combination with a locomotive having a boiler, an injector, and a firebox, a pre-heating tube extending through the firebox, a settling tank communicating with one end of said tube, a return tube from the boiler, a valve connecting the other end of said pre-heating tube to the injector and to the return tube, said valve being adapted to automatically establish communication between the injector and pre-heating tube when the injector is in action, and between the return tube and pre-heating tube when the injector is not in action, and an injecting tube connecting the settling tank with the boiler.

6. In combination with a locomotive having a boiler, two injectors and a firebox, a pair of pre-heating tubes extending through the firebox, a return tube communicating with the boiler, a pair of valves connecting said preheating tubes with said return tube and with the respective injectors, and adapted through the operation of either injector to establish communication with the latter and its respective preheating tube and to cut off such communication with the injector when the injector is shut off, and establish communication between the return tube and said pre-heating tube, a settling tank communicating with the pre-heating tubes, and an injecting tube connecting the settling tank with the boiler.

7. In combination with a locomotive having a boiler, two injectors and a firebox, a pair of pre-heating tubes extending through the firebox, a return tube communicating 130

with the boiler, a pair of valves connecting said preheating tubes with said return tube and with the respective injectors, and adapted through the operation of either injector to establish communication with the latter and its respective preheating tube and to cut off such communication with the injector when the injector is shut off, and establish communication between the return tube

10 and said pre-heating tube, and an injecting tube connecting the other ends of the preheating tubes with the boiler.

8. In combination with a boiler having a firebox, a settling tank, a pair of preheating tubes extending through the firebox and communicating with said settling tank, adapted to convey feed water to the tank either singly or together, an injecting tube connecting the upper portion of the tank 20 with the boiler, the junctures of the preheating tubes with the tank being disposed at points spaced from each other circumferentially of the tank, a horizontal baffle plate in the settling tank to prevent direct flow of 25 water from either of the preheating tubes to the injecting tube, and a vertically posi-

tioned baffle plate supported from said horizontal baffle plate, positioned to prevent direct flow of feed water from one of the preheating tubes to the other. 30

9. In combination with a boiler having a firebox, and two injectors, a settling tank, a pair of preheating tubes extending through the firebox and communicating with said settling tank at points spaced from each other circumferentially of said tank, an injecting tube connecting the upper portion of the tank with the boiler, a return tube, means connecting the preheating tubes and injectors and return tube in such manner that when one injector is in action it will force water through one of the preheating tubes into the settling tank, while the other preheating tube will be in communication with the return tube, and a baffle plate in 45 the tank positioned to prevent direct flow of feed water between the preheating tubes. 40

Signed at Sioux City, in the county of Woodbury and State of Iowa, this 15th day of January, 1925.

MICHAEL M. CROWLEY.
